UNITED STATES PATENT OFFICE.

MICHAEL GILSON, OF PORT WASHINGTON, WISCONSIN, ASSIGNOR TO KWIK-MIX CONCRETE MIXER CO., OF PORT WASHINGTON, WISCONSIN.

CONCRETE MIXER.

Application filed April 14, 1927. Serial No. 183,703.

This invention relates to mixing machines and is particularly directed to a concrete mixer.

Objects of this invention are to provide a novel form of concrete mixer in which a mixing vessel is provided and associated with a charging bucket, and in which means are provided for elevating the charging bucket so that it is raised bodily and tilted to empty into the charging vessel, the means for raising and guiding the bucket being so constructed that the bucket rocks about a continuously shifting center during its elevation.

Further objects are to provide a mixing machine in which the guiding means is formed in pairs and located on opposite sides of the bucket with one member of each pair constituting a track and the other member constituting a rolling curved means traveling upon the track, and to provide flexible suspension elements for the inner end of the bucket adapted to be received within the rolling member, such rolling member being channel-shaped for the reception of the flexible elements.

Further objects are to provide a novel form of concrete mixer which is of extremely simple and eminently practical construction, which may be cheaply made, and which supports a bucket in a manner to permit its ready shaking to dislodge the material therefrom.

An embodiment of the invention is shown in the accompanying drawings, in which:

Figure 1 is a sectional view on the line 1—1 of Figure 3, showing in full lines the bucket in charge receiving position, and in dotted lines in discharging position.

Figure 2 is a fragmentary view of the guiding means showing the bucket partly elevated.

Figure 3 is a plan view of the structure shown in Figure 1.

Referring to the drawings, it will be seen that the concrete mixer chosen for illustration consists of a mixing vessel 1 carried in the usual manner by a frame 2. This frame is provided with plates 3 on opposite sides and the plates 3 carry tracks 4 formed of angle iron with the flanges 4' located on the outer sides, as may be seen from Figures 1 and 3. The frame is also provided with guiding pulleys 5 for the elevating cables 6.

The charging bucket 7 is carried by a pair

of channel iron bars 8 which extend diagonally inwardly when the bucket is in its lowermost position, as shown in full lines in Figure 1. These channel iron bars 8 carry channel-shaped rolling means 9 which are adapted to travel upon the track 4, as shown in Figures 1 and 2. The members 9, as stated, are adapted to receive within themselves flexible suspension means which may take the form of a chain 10 and which is duplicated on opposite sides of the machine. These suspension elements or chains are secured at their upper ends to the frame through the medium of the track and at their lower ends to the rolling channel shaped members 9.

If desired the tracks 4 may have inwardly turned upper portions 11 so as to permit a quick inward motion of the bucket at the completion of its upward stroke, so as to start the material downwardly and inwardly from the bucket.

From the description and illustration, it is apparent that when the outer end of the bucket is elevated, the members 9 will roll upon the track 4 and will wind up the chains 10. This is also readily apparent from the fact that the bucket tends to rock inwardly and constantly forces the rolling members 9 into contact with the track 4. As the bucket is elevated it rocks about a continuously shifting center. This permits the necessary motion or translation for elevating the bucket bodily and also imparts to the bucket a rocking motion to cause it to discharge into the mixing vessel when it is in the dotted line position shown in Figure 1.

It is to be noted particularly that the suspension members permit the ready lateral shaking of the bucket with the utmost ease as it is not rigidly connected to the framework, but is suspended by flexible members. This results in the ready loosening of any adhering material and its discharge into the mixing vessel.

It is to be noted, also, that scarcely any machine work is required in the production of this type and that the parts may be readily formed from standard stock with the utmost cheapness. Further it will be seen that the device is eminently practical and is of rugged and substantial formation.

Although the invention has been described in considerable detail, such description is in-

tended as illustrative rather than limiting as the invention may be variously embodied and as the scope of such invention is to be determined as claimed.

5 I claim:—

1. A mixing machine comprising a mixing vessel, a frame supporting said vessel, a charging bucket, elevating means for raising the outer end of said bucket, and guiding means adjacent the inner end of said bucket, said guiding means consisting of a pair of guiding elements located on opposite sides of said bucket and each pair consisting of a track and a curved member for rolling upon said track, and flexible means for suspending said bucket adjacent its inner end, the lower ends of said tracks being located inwardly beneath said mixing vessel, whereby as said bucket is raised, the center about which it pivots moves upwardly and outwardly with reference to said mixing vessel.
- 10 2. A mixing machine comprising a mixing

vessel, a frame supporting said vessel, a charging bucket, elevating means for raising the outer end of said bucket, guiding means adjacent the inner end of said bucket,

25

said guiding means consisting of a pair of guiding elements located on opposite sides of said bucket and each pair consisting of a track and a curved member for rolling upon said track, and flexible means for suspending said bucket adjacent its inner end, the lower ends of said tracks being located inwardly beneath said mixing vessel, whereby as said bucket is raised, the center about which it pivots moves upwardly and outwardly with reference to said mixing vessel.

30

In testimony that I claim the foregoing I have hereunto set my hand at Port Washington, in the county of Ozaukee and State of Wisconsin.
